John D. Patterson Jason Hill,
Wm. Jewell By atty. A. J. Strongton.

United States Patent Office.

JASON HILL, OF ASTWOOD, NEAR REDDITCH, ENGLAND

Letters Patent No. 70,716, dated November 12, 1867.

IMPROVEMENT IN WRAPPERS FOR NEEDLES.

The Schedule referred to in these Letters Patent and making part of the same.

TO ALL WHOM IT MAY CONCERN:

Be it known that I, JASON HILL, of Astwood, near Redditch, in Worcestershire, England, have invented certain new and useful Improvements in the Manner of Putting up Needles in Wrappers; and I do hereby declare the following to be a full, clear, and exact description of the same, reference being had to the accompanying drawings, making a part of this specification, in which—

Figure 1 represents a package of needles in its wrapper, and as it appears when two folds of the wrapper are opened and the flap turned back.

Figures 2 and 3 represent modifications of the same general plan of putting up the needles and gaining access to them without handling them.

Figures 4, 5, and 6, respectively, represent the shape, form, fold, and location of the needles, (in the wrappers or papers shown in figs. 1 2 3, in a partially folded state,) when said packages or papers are entirely unfolded.

I am aware that many forms or ways of putting up needles to prevent them from dropping, or corrosion from handling, have been devised and used, but I have seen none where the needles are so easily and readily accessible as by my plan, and at the same time so secure from handling or corrosion.

To enable others skilled in the art to make and use my invention, I will proceed to describe the same with reference to the drawings.

Fig. 1 represents one form of wrapper or plan of putting up the needles, and in the position it would be when partially opened up to gain access to the needles, which are seen at *a*. To close up this package, the flap *b* is first laid down upon the needles, then the lower end *c* of the package is folded up and against the flap *b*, and then the upper portion *d* is turned down and the lower portion stuck into it, or *vice versa*. The reverse of this operation opens up the package, as will be readily understood. In fig. 4 I have shown, though on a reduced scale, the appearance of the package, fig. 1 when entirely unfolded, the dotted lines representing the creases made by the foldings. This wrapper when spread out is in the form of a quadrangular figure, with an angular flap, *b*, on one of its ends. The needles *a* having been stuck into strips of paper or cloth, *e*, fastened to or laid in the wrapper or envelope, or having been stuck in the wrapper or envelope itself, so that the tops of the needles shall be opposite the opening *f*, then the wrapper is folded down first at the crease 1, then this double thickness is folded over at the crease 2, which brings the package into the form shown in fig. 1; then, as above mentioned, the flap *b* is laid down, the portion *c* folded up, and the top *d* turned down, and the two "pocketed" one into the other in the well-known way.

By this plan of wrapping or enveloping needles, the user can take the package in the left hand and open or hold it in said hand, whilst with the other hand a needle may be selected and the package again closed by the left hand, without handling or soiling the needles or allowing them to drop.

This general description covers the other modifications of wrappers shown in figs. 2, 5, and 3, 6. As shown in fig. 2, the flap *b* is quadrangular, and as also seen in fig. 5, the wrapper is of a rectangular or square form, and has two cuts, *g* *h*, made in it. The needles in this case are stuck in a separate strip of paper or cloth, which may be pasted to the flap *i*, that is formed in making the opening through which the heads of the needles are seen, selected, and the needle drawn out. This wrapper or envelope is first folded at the crease 1, then at the crease 2, then the flap *j* is turned down, or it and the flap *b* both turned down together; then the part *c*, and finally the portion *d*, which latter may be pocketed together, or pasted, or otherwise fastened for transportation. The cut or slash *h* in the wrapper may be dispensed with. It will be seen, however, that in this as in that shown at fig. 1, the user can hold and open the package with the left hand, whilst the right hand may draw out the selected needle and the package again closed by the left hand without handling, soiling, or dropping the needles. And further, that in opening the wrapper, the flap *b* swings to the left, as in that shown in fig. 1.

In figs. 3 and 6 the same general form and characteristics are shown, the difference being only in the size of the flaps *b* and *j*, and the heads of the needles showing on the back of the wrapper, instead of through an opening in the wrapper. The flap *b* swings to the left in opening up access to the needles, and it is held down by folding *c* and *d* against it.

Having thus fully described my invention, what I claim therein as new, and desire to secure by Letters Patent, is—

In combination with a wrapper in or on which needles are placed or stuck, an incision or flap at or near the upper left-hand corner, for forming a cover for and for gaining access to the tops of the needles, substantially as and for the purpose described.

JASON HILL.
